UNITED STATES PATENT OFFICE.

BRUNO WEBER, OF VEEDERSBURG, INDIANA.

DESIGN FOR A PAVING-BRICK.

SPECIFICATION forming part of **Design No. 28,376**, dated **March 15, 1898**.

Application filed November 10, 1897. Serial No. 658,101. Term of patent 7 years.

To all whom it may concern:

Be it known that I, BRUNO WEBER, a citizen of the United States, residing at Veedersburg, in the county of Fountain and State of

5 Indiana, have invented and produced a new and original Design for Paving-Bricks; and I do declare the following to be a full, clear, and exact description of the same, reference being had to the accompanying specification and drawings, forming a part thereof.

Figure 1 is a perspective of my paving-brick, showing my new design. Fig. 2 is a side elevation thereof. Fig. 3 is an end elevation thereof.

5 As shown in the drawings, my design for a brick consists of a figure substantially rectangular and parallelepiped in form. The edges of the figure are all curved or rounded, substantially as shown. Longitudinally and centrally along two opposite sides of the figure

are lines indicating a kerf, recess, or depression 1, which is angular in cross-section, as shown. The other sides and ends of the figure are smooth and plain.

The leading or characteristic features of 25 my design comprise the unitary article shown in the drawings—that is to say, a paving-brick rectangular in outline, with rounded corners, and provided with the oppositely-disposed kerfs, as shown. 30

What I claim as my invention, and desire to secure by Letters Patent, is—

The design for a paving-brick shown and described.

In testimony whereof I affix my signature 35 in presence of two witnesses.

BRUNO WEBER.
